UNITED STATES PATENT OFFICE.

EDWIN J. ELLIS, OF AURORA, ILLINOIS.

INTERNAL-COMBUSTION ENGINE.

1,205,606.

Specification of Letters Patent. Patented Nov. 21, 1916.

Application filed February 25, 1914. Serial No. 820,939.

To all whom it may concern:

Be it known that I, EDWIN J. ELLIS, a citizen of the United States, residing at Aurora, in the county of Kane and State of Illinois, have invented new and useful Improvements in Internal-Combustion Engines, of which the following is a specification.

This invention relates to internal combustion engines and particularly to the valve mechanism which takes care of the intake of the fresh charges of explosive mixture and the exhaust of the burned gases from the several cylinders of the engine.

15 The object of the invention is to provide in connection with a plurality of cylinders arranged in tandem relation to each other, a rotary tubular distributing and collecting valve or, in other words, a single valve 20 which is adapted to distribute the charges of the mixture to the several cylinders and also collect or receive the exhaust gases from the cylinders.

25 With the above and other objects in view, the invention consists in the novel construction, combination and arrangement of parts, as will hereinafter be more fully described, illustrated and claimed.

In the accompanying drawings:—Figure 30 1 is a vertical longitudinal section through a multiple cylinder internal combustion engine embodying the present invention, said section extending diametrically through the inlet and exhaust valve. Fig. 2 is a vertical 35 cross section taken diametrically through one of the cylinders, showing the intake position of the valve. Fig. 3 is a similar view showing the exhaust position of the valve. Fig. 4 is a detail vertical cross section on the line 4—4 of Fig. 1. Fig. 5 is a detail section similar to the upper portion of Fig. 2 showing the use of a duplex rotary valve.

40 Referring to the drawings 1 designates the crank shaft of a multiple cylinder engine, 2 the crank case, 3 the cylinders, 4 the pistons and 5 the connecting rods, the engine being of the ordinary four-cycle reciprocating piston type and the cylinders being 45 water jacketed as at 6.

In carrying out the present invention, I employ a multiple cylinder head designated generally at A, said cylinder head being common to all of the cylinders 3. The cylinder head A comprises an inner wall 7 which 50 may be said to constitute the cylinder head

proper, and an outer semi-cylindrical wall 8 which forms a water jacket around the valve casing, the latter being designated at 9 and being substantially cylindrical and 55 tubular in cross section.

The valve casing or tube 9 extends throughout the entire length of the multiple cylinder head and is formed integrally with the inner wall 7, the latter being provided at the outer end of the combustion chamber of each of the cylinders 3 with a single port 10 which forms at one and the same time the charge intake port and the 60 exhaust port.

Revolutionarily mounted in the valve casing 9 is a tubular cylindrical distributing and collecting valve 11. On its outer surface this valve is in the form of a true cylinder and has a close working fit within the casing 9 65 so as to avoid leakage of the gas. The valve comprises an outer shell to which the reference numeral 11 is applied and also comprises an inner shell 12 concentric with the outer shell but made tapering or gradually 70 increasing in diameter toward its discharge end where it is open as shown at 13 so as to discharge into the adjacent end of an exhaust pipe 14 or if preferred to the atmosphere direct.

75 The outer shell of the valve is formed at intervals with supply or distributing ports 15 arranged at suitable intervals around the shell 11 to register at the proper periods with the ports 10 of the several cylinders 80 in order to charge said cylinders with explosive mixture. The inner or exhaust shell 12 is likewise provided with a corresponding number and arrangement of receiving or collecting ports 16 which are defined by 85 tubular necks 17 leading from the inner shell 12 to the outer shell 11 as clearly shown in the cross sectional views. The port 15 of any one cylinder is arranged 90 approximately 90° from the port 16 in order that after a cylinder is charged with gas, the piston may complete its suction stroke and the compression and firing strokes before the exhaust port 16 comes into line with the port 10 in the cylinder head, whereupon the exhaust gas is thoroughly scavenged from said cylinder by the outward 95 stroke of the piston 4 the same as in any ordinary four-cycle engine.

100 At one end the outer and inner shells are connected by suction vanes 18 resembling fan blades, the pitch of which is so designed 105

as to suck in the explosive mixture from the intake pipe 19 which connects with a suitable carbureter (not shown). This end portion of the valve is journaled in and is closed by a tubular extension 20 of the multiple cylinder head as shown in Fig. 1 and extending beyond the end of the rotary valve is a shaft 21 upon which is mounted a wheel 22 adapted to be driven by the crank shaft 1. While the driving of the rotary valve may be accomplished by any suitable driving mechanism interposed between the crank shaft and the valve shaft, I prefer to use a silent chain 23 passing around the wheel 22 and also around another wheel 24 on the crank shaft. The same chain 23 may be employed to operate the cooling fan 25 by working over a wheel 26 on the fan shaft 27.

20 By making the inner shell 12 tapering from end to end, the charge containing chamber 28 gradually decreases in capacity from its receiving end in order to properly supply the mixture in the necessary quantity to the cylinders arranged in tandem. Furthermore, the exhaust passage or chamber 29 correspondingly increases in diameter toward its discharge end to enable it to efficiently collect and discharge the exhaust 25 gases received from the cylinders. The exhaust gas by passing constantly through the chamber 29 formed by the inner shell 12 also serves to heat the incoming mixture and fully vaporize the same thereby economizing in fuel and producing the highest efficiency possible.

The collecting and distributing valve hereinabove described is preferably formed of high grade cast iron which is heat treated so 40 as to reduce the expansion and contraction to a minimum. On account of the constant rotation of the valve, there is no chance for carbon and other deposits to collect on the valve or within the valve casing, the valve 45 being in effect self-cleaning. Furthermore there is comparatively little friction to the revolution of said valve as the ports leading through the cylinder heads are relatively small as compared with the bearing 50 surface of the valve. By thus doing away with carbon deposits, the engine is easily maintained at its full efficiency and will be found much more reliable than the ordinary puppet valve construction in which carbon 55 rapidly accumulates around the valves and their seats and by preventing the proper seating of the valves soon results in a very considerable reduction in the power and efficiency of the engine.

60 In some cases it may be desirable to increase the rapidity with which the intake and exhaust ports open and close and in such cases a supplemental shell 30 may be placed around the outer shell 11 above described and formed with intake and exhaust

ports to register with the ports 15 and 17 above described. This supplemental shell 30 may be driven or rotated in the opposite direction from the valve hereinabove described thereby reducing the opening and closing movements of the ports one-half. This may also be accomplished by varying the sizes of the ports in the cylinder head and in the outer and inner shells of the valve. By the valve arrangement hereinabove described, all lateral or offset valve chambers are dispensed with and this enables higher compression of the gases to be obtained which is productive of stronger impulses for a less amount of mixture. This produces an engine which is economical in operation.

The construction herein described and shown provides tapering concentric exhaust and intake manifolds and by reason of the fact that the device as a whole revolves, uniform heating and cooling is obtained, the increasing diameter of the exhaust manifold preventing excessive heating as additional charges are received from the cylinders along the concentric rotating exhaust manifold. A ground working fit is obtained on the outside of the manifold valve the entire length of the combined distributing and collecting concentric chambers, resulting in a practically total elimination of pull as there is no load or strain of any character on the manifold valve itself, thereby assuring longer service and maintaining at all times a perfectly tight working fit. Should any perceptible wear occur the possibility of leakage from one cylinder to another will be prevented by the rings which surround the manifold valve between each of the cylinders. The compression and explosion strokes serve to hold the rotary manifold valve against the upper wall of the chamber or casing in which it works so that an oil film will perfectly seal the same allowing no pressure to escape except through the register ports of the cylinder and manifold valve.

It will also be noted that the rotary intake and exhaust manifold valve is cast in one piece without any joints and is therefore not liable to warpage or leakage from expansion and contraction and there are no surfaces to be machined with the exception of the single outside surface. This elimination of joints alone is an important factor in the practical working and maintenance of the efficiency of the valve. The ports are elongated longitudinally of the manifold valve thus enabling each port to be fully opened and fully closed on a comparatively short travel of the piston on the intake or exhaust stroke. The cooling circulation is entirely cut off from any working joint or surface and hence no water can possibly enter the manifolds or cylinders. My

method of cooling the exhaust manifold, and port walls of the same, on all exterior surfaces with the cool incoming gas, keeps the exhaust surfaces heated alike. The incoming gas going between the walls of the exhaust manifold and the wall of the intake manifold, holds the temperature of the working surface uniform with the chamber wall containing the rotary manifold valve. The cooling water circulating around this chamber wall brings the temperatures of both to substantially the same degree, which is not high, and therefore said surfaces are uniformly heated along their entire length so that the fit and lubrication are practically perfect.

What I claim is:—

1. In a multiple cylinder internal combustion engine, a rotary tubular charge-distributing and exhaust-collecting manifold valve common to all of the cylinders, said valve comprising an outer cylindrical shell provided with a lateral intake orifice adjacent to one end thereof and having a supply port for each cylinder, and an inner shell concentric with the outer shell closed at one end and having an exhaust-collecting port for each cylinder, said inner shell terminating at its closed end short of the lateral intake orifice of the outer shell and being open at

its other end, the inner shell having a progressively increasing internal and external diameter from its closed end toward its discharge end.

2. In a multiple cylinder internal combustion engine, a rotary tubular charge-distributing and exhaust-collecting manifold valve common to all of the cylinders, said valve comprising an outer cylindrical shell provided with a lateral intake orifice adjacent to one end thereof and having a supply port for each cylinder, an inner shell concentric with the outer shell closed at one end and having an exhaust-collecting port for each cylinder, said inner shell terminating at its closed end short of the lateral intake orifice of the outer shell and being open at its other end, the inner shell having a progressively increasing internal and external diameter from its closed end toward its discharge end, and suction vanes carried by said valve and having their peripheral edges arranged to sweep across said lateral intake orifice.

In testimony whereof I affix my signature in presence of two witnesses.

EDWIN J. ELLIS.
